CHECKER-BRICK AND CHECKERWORK CONSTRUCTION

Application filed July 10, 1930. Serial No. 467,094.

This invention relates to new and useful improvements in checker-brick and checker work construction particularly adapted for use in regenerator-furnaces and the like, and involves essentially a novel type checker-brick and checkerwork adapted to provide maximum radiating surface without lessening the stability and efficiency of the construction.

10 The primary object of this invention is to provide a novel checker-brick having maximum heating surface in relation to cubical content.

15 It is a further object of this invention to provide a checker-brick free from undesirable cold center points which arise from absorption of heat by the brick with only partial radiation due to excessive cubical content for the available heating surface.

20 It is a further object of this invention to provide a checker-brick which is efficient, cheap, possessing a stability which minimizes replacements, and of such shape as to allow the construction of a checkerwork having great rigidity and strength.

25 It is another object of this invention to provide a checker-brick so designed that when the same is in place in a checkerwork, there will be no broad surfaces exposed for the deposition of flue dust which tend to clog the horizontal flues and the furnace archings over the vertical flues.

30 Still another object is to provide a checker-brick for use in checkerwork construction which will give vertical and horizontal flue areas adapted to allow free passage of the furnace gases to all parts of the setting without lessening the heating and radiating surface areas of the respective bricks in the construction.

35 A further object is to provide a checker-brick having one sloping wall which not only increases the vertical and horizontal flue areas of a checkerwork, but also provides novel diagonal flues adapted to direct the flow of gases or baffle the same in accordance with the manner in which the sloping surfaces of the bricks in adjacent layers and rows are arranged with respect to each other.

40 Other objects and advantages of my novel

checker-brick and checkerwork will in part be obvious and in part become apparent as the description proceeds.

In the accompanying drawing I have illustrated the preferred embodiments of my invention, but it is to be understood that the same is capable of a reasonable degree of modification and equivalency with respect to size, proportions, and arrangement of parts without departing from the spirit and scope thereof as determined by the appended claims.

In the drawing:

Fig. 1 is a perspective view of my novel checker-brick;

Fig. 2 is a view in perspective, illustrating generally the manner in which checker-bricks of the type shown in Fig. 1 may be set in layers and rows to form a checkerwork;

Fig. 3 is a view in vertical section of a checkerwork showing in particular the definitely defined diagonal flues and directory influence on the gases made possible by the use of my novel checker-brick; and

Fig. 4 is a view in vertical section of a checkerwork differing from the arrangement of bricks in Fig. 3 in that the sloping surfaces of the alternate layers of brick are oppositely disposed to cause a baffling of the gases between the various vertical flues.

Referring now to the drawings, I have, in Fig. 1, shown a preferred embodiment of the checker-brick which constitutes the essence of my invention. In its outside dimension it may conform to those of any standard type checker-brick.

The ends of the brick may be square or rectangular for the purpose of providing convenient and stable support for adjacent bricks when the same are set up in a checkerwork construction. Such ends, however, are not essential and any convenient means may be utilized to enable the bricks to be assembled to form a firm construction.

The essential feature of my checker-brick is the cross-sectional shape of the brick intermediate the square or rectangular ends, whereby the heating surface will be so related to the cubical content of the brick as to eliminate the danger of cold spots in the interior of the brick, and I accomplish this without eliminating the flat base and

one vertical face. I have found that by providing a sloping surface intermediate the ends of the brick cutting the top and one face of the brick and whose plane intersects the plane of the other face and bottom at an angle less than 90 degrees, a maximum heating or radiating surface will be provided in relation to the cubical content so that no point within the brick is so far distant from one of the faces or the sloping surface as not to be readily heated.

Referring to the figure, 10 denotes, generally, my checker-brick, which, as above pointed out, may have square or rectangular ends. Intersecting the sides 11 and 12 intermediate the ends is a sloping surface 13 which, as shown in Fig. 3, is so related to the bottom 14 and the flat side 15 that any point within the interior of the brick between such sloping surface and the bottom and face is relatively close to the surface. While for purposes of stable construction I prefer to have the sloping surface 13 intersect the top 11 and side 12 along lines slightly removed from the lines of joinder of the top 11 and side 15 and the side 12 and bottom 14, it will be understood that such construction is not necessary but, on the other hand, the boundaries of the sloping surface 13 may be defined by the lines of intersection of the sides with the top and bottom so that in cross section the brick will have the shape of a true right angle triangle. While the side and bottom may be of different widths, I prefer to have them equal so that the angle formed between the sloping surface and the bottom and side will be 45 degrees, as, by experiment, it has been demonstrated that the best ratio of heating surface to cubical content will thus be obtained.

Not only does the above described checker-brick have a greater efficiency, due to a better ratio between the heating surface and the cubical content, but possesses certain additional advantages which make it admirably suited for use in checkerwork construction for regenerative furnaces. By reason of the angular relation between the sloping surface and the side of the brick, the furnace gases will be subjected to a directory influence. Referring to Fig. 2, which shows the manner in which bricks of my novel design may be assembled in layers and rows to constitute a checkerwork, it will be evident that not only are vertical and horizontal flues formed by reason of the setting of the bricks, but also, due to the provision of the sloping surfaces on the bricks, the furnace gases will be directed diagonally from one vertical flue to the adjacent flue formed between oppositely disposed bricks with the result that the furnace gases will be brought in contact with more of the surface of the checkerwork. Thus, gases which come into the vertical flue defined in part by the checker-bricks 16, 17,

18 and 19, will be directed downwardly and outwardly from said vertical flue by reason of the sloping faces 20, 21 and 22 on the respective bricks 17, 18 and 19.

The directory effect on the gases which is made possible by reason of the sloping surface on the checker-bricks may be regulated at will in accordance with the location of the sloping surfaces on the bricks in adjacent columns and rows. The construction shown in Fig. 3 corresponds to the arrangement of bricks shown in the perspective view Fig. 2 wherein the sloping surfaces of all of the bricks in adjacent rows and columns face in the same direction with the result so that the gases are directed diagonally downward from left to right. Assuming that gases enter the checkerwork from the left, such as would be true if the bridge wall is located at this end and the stack at the right, such gases as enter the vertical flue defined in part by the bricks 26 and 27 will be baffled downwardly by the vertical face 23 of the brick 24 and will be given a diagonal direction by the face 25 of the brick 26. Gases entering through the horizontal flue defined by bricks 26 and 28 will be directed downwardly at an angle by the sloping surface 27 of brick 28 in cooperation with the oppositely disposed vertical face 29 of the brick 30.

A further important advantage arising by reason of the utilization of a brick having substantially triangular cross section, resides in the fact that both the horizontal and vertical flue areas are substantially increased without lessening the available heating surface as determined by the individual bricks making up the checkerwork. With the larger flue areas, there will be less tendency for flue dust to deposit on the bricks and the gases will be allowed free passage to all parts of the setting.

In Fig. 4, I have shown another manner in which my novel type of checker-brick may be utilized in a checkerwork construction differing from that shown in Fig. 3 in that adjacent bricks in the several vertical columns have their sloping faces oppositely disposed for the purpose of baffling the furnace gases backwards and forwards between adjacent flues, instead of utilizing the sloping surfaces of bricks in oppositely disposed columns merely to give the gases a diagonally downward direction from one end of the checkerwork to the other. Thus, gases impinging on the sloping surface 32 of the brick 31 will be directed downwardly at an angle to the left, and, mingling with other gases, will impinge on the oppositely disposed sloping surface 34 of the brick 33 to be given a downward diagonal direction towards the right.

It will be clear from the above described checkerwork constructions that my novel type brick possesses numerous advantages over

what has heretofore been known in the art and gives rise to certain desirable features in checkerwork construction which tend to increase the efficiency of the same. Many 5 different arrangements of the bricks in the various rows and columns may be made to effect any desired result. The particular features which arise from the utilization of my brick in checkerwork and which would be common to all types of construction are 10 that the horizontal and vertical flue areas in the checkerwork are increased, distinct diagonal flues are created and, by reason of the sloping surface of the bricks, the furnace gases may be directed through all parts 15 of the setting and, if desirable, baffled back and forth between adjacent vertical and horizontal flues.

I am aware that it has heretofore been 20 proposed to construct checkerwork bricks having a flat base and either conversely curved or flat sloping sides terminating in an upper edge. Certain advantages of my checker-brick over such type of brick will 25 be readily understood from a comparsion of checkerwork construction made from the respective types of brick. With the brick having a wedge shaped cross section, since both 30 of the sides of the brick slope upwardly, no directory influence can be exercised on the furnace gases, whereas with my checker-brick I am able to exercise a directory influence on the gases between the sloping surfaces of 35 the bricks in one vertical column of a check- 40 erwork in cooperation with the vertical faces of corresponding bricks in adjacent oppositely disposed vertical columns. Furthermore, my checker-brick, taken as a unit, possesses an advantage over the various types 45 of brick heretofore known in the art in that, by reason of the design of the brick to have a flat bottom and flat vertical side in connection with an oppositely disposed sloping 50 surface, the heating surface bears a better relation to the cubical content and is such as to minimize the danger of cold spots in the 55 inner portion of the brick.

I claim:

1. A checker-brick of rectangular cross- 50 section in portions of its length, two of whose adjacent faces are flat throughout its length, the other two faces being cut away for another portion of the length so as to form a sloping surface which with the first two adjacent faces forms substantially a right angle 55 triangle.

2. A checker-brick having a flat base and 60 a flat vertical face at right angles to the base, said base and face being continuous throughout the length of the brick, the brick 65 being provided with end portions formed to support the brick in a checkerwork and having a cross-sectional area for the major portion of its length approximating a right angle triangle.

3. A checker-brick of high ratio of heating surface to cubical content having two faces continuously flat throughout the length of the brick, and for the major portion of its length having a cross-sectional area approximating a right angle triangle defined by a surface including a third face angularly related to the first two faces, the brick 70 in other portions of its length being provided with a surface parallel with the base 75 adapted to support the brick in a checkerwork.

4. A checker-brick having two adjacent faces continuously flat throughout the length of the brick and disposed at right angles, 80 and for the major portion of its length having a third face forming approximately 45 degree angles with the first two faces to define in such portion a cross-sectional area of substantially right angle triangular shape, 85 the brick in other portions having a horizontal surface parallel with one of the first mentioned faces to support the brick with relation to other bricks in a checkerwork.

5. A checkerwork construction comprising 90 in combination a plurality of horizontal rows of brick arranged in columns and extending at right angles to adjacent rows to form vertical and horizontal flues, the bricks 95 each having ends formed with parallel horizontal surfaces adapted to support the brick in relation to other bricks and having a flat base and a flat vertical face at right angles to the base extending throughout the length of the bricks, the bricks for the major portion 100 of their length also each having a sloping face defining with the base and vertical face in such portions a substantially right angular cross-section, the sloping faces of 105 the bricks defining diagonal flues between adjacent horizontal and vertical flues.

In testimony whereof, I affix my signature.
